US0D1112598S

(12) **United States Design Patent** (10) **Patent No.:** **US D1,112,598 S**
(45) **Date of Patent:** **** Feb. 10, 2026**

(54) **WATER PURIFIER**

(71) Applicant: **Bluevua Inc.**, Spokane, WA (US)
(72) Inventors: **Ling Yan**, Suzhou (CN); **Yasu Wang**, Suzhou (CN); **Celina Gu**, Arlington, TX (US); **Weiwu Zuo**, Suzhou (CN)
(73) Assignee: **Bluevua Inc.**, Spokane, WA (US)

(***) Term: **15 Years**

(21) Appl. No.: **29/923,883**

(22) Filed: **Jan. 2, 2024**

(30) **Foreign Application Priority Data**

Jun. 30, 2023 (CN) 202330407275.7

(57) **CLAIM**

The ornamental design for a water purifier as shown and described.

DESCRIPTION

FIG. 1 a front elevational view is of a water purifier showing our new design;

FIG. 2 is a rear elevational view thereof;

FIG. 3 is a left elevational view thereof;

FIG. 4 is a right elevational view hereof;

FIG. 5 is a top plan view thereof;

FIG. 6 is a bottom plan view thereof; and,

FIG. 7 is a front perspective view thereof.

The broken lines shown in the figures are for the purpose of illustrating portions of the water purifier and form no part of the claimed design.

1 Claim, 7 Drawing Sheets
